UNITED STATES PATENT OFFICE

2,594,112

WASHING MACHINE PROVIDED WITH LOADING AND UNLOADING PASSAGEWAY

Oscar M. Anderson, New Britain, Conn., assignor, by mesne assignments, to Crosley Division, Avco Manufacturing Corporation, Cincinnati, Ohio, a corporation of Delaware

Application April 25, 1947, Serial No. 743,843

3 Claims. (Cl. 68—24)

1

The present invention relates to laundry machines of the type having a tub and rotatable drum assembly resiliently mounted for vibrational and gyrating movement within a casing, and more particularly to a loading and unloading passageway between the casing and tub of such machines which is effective and has many advantages for the purpose intended and which does not interfere in any way with the operation of the machine.

In laundry machines of the type referred to the tub unit comprising a tub and a basket journaled therein is subjected to various vibrations and gyratory actions which are largely due, for example, to unbalanced conditions as when the fabrics are not uniformly distributed within the basket. The present invention is particularly applied to laundry machines of this sort which are provided with resilient mounting means for permitting and absorbing such relative movements of the tub unit with respect to the casing in any direction in the plane of rotation of the tub unit as well as some endwise movement of the tub unit. It may be pointed out, in addition, that in laundry machines of such construction and mounting the tub unit will generally move from an upper fluid extraction position to a lower washing position upon the admission of a cleaning fluid to the tub and also dependent to some extent upon the weight of the clothes placed therein.

It is an object of the present invention to provide a loading and unloading passageway between the casing and the tub unit which will permit said gyratory movements of the tub unit with respect to the casing and which will be effective at any of the different spacings between the casing and the tub unit, such as the difference in spacing when the tub unit is filled with cleaning fluid and when the cleaning fluid is drained therefrom.

A further object of the invention is to provide such a passageway which will not interfere with the action or movements of the tub unit, which is not dependent on flexible or foldable connectors and the like which might be likely to deteriorate or malfunction, particularly after long periods of hard usage.

A further object of the invention is to provide a loading and unloading passageway between the casing and tub unit which is of pleasing, streamlined appearance, which provides an attractive and utilitarian housing in which the door or other opening means for the tub unit may be

2

pivoted, and which will retain an immaculate and sanitary appearance over long periods of time.

A further object of the invention is to provide a passageway construction of the type described which, although forming no positive engagement between the casing and tub unit, will insure that no drainage from clothes being introduced or removed from the tub, nor the clothes themselves, can pass inside the casing or otherwise come into contact with the mechanical elements of the machine.

A further object is to provide a passageway construction, as described, which is simple and economical to manufacture and to assemble and disassemble.

Other objects will be in part obvious and in part pointed out more in detail hereinafter.

The invention accordingly consists in the features of construction, combination of elements and arrangement of parts which will be exemplified in the construction hereafter set forth and the scope of the application of which will be indicated in the appended claims.

In the drawing—
25 Figure 1 is a fragmentary view partially in cross section through the center of the machine embodying the invention; and

Fig. 2 is a top view of the machine partially cut away and in cross section to show the mounting of the tub unit.

In the drawing, the machine embodying the present invention is housed in a casing 9 formed of an upper section 10 and a lower section 11 joined together at flanges 12. A supporting frame 8 is provided within the casing section 11. The tub unit denoted generally by the reference numeral 13 and comprising a tub 14 and a rotatable basket 15 journaled therein is mounted horizontally within the casing. The means for mounting the tub unit 13 is only partially shown in the drawing and may comprise any suitable mounting means for permitting gyrational movement of the tub unit 13 in any direction in the plane of rotation of the basket 15 while restricting and damping same. In the embodiment shown in the drawing, the tub unit 13 is mounted on a frame member 30 which is suspended from the frame 8 by means of springs 31 which resiliently support the tub structure and absorb the vibrational forces so that they are not transmitted to the frame 8 and hence to the floor. Damping units comprising a pair of links 32 pivotally connected to each other and to the frame 8 through friction washers 33 limit the amplitude of vibration of the tub structure. The

links 32 restrainingly permit movement of the tub structure in any direction in the plane of rotation of the basket 15 as well as endwise movement of the tub unit. The casing 9 is substantially stationary so that the gyroscopic movements of the tub unit 13 are relative to the casing 9.

In accordance with the invention, the tub unit 13 is constructed and arranged to permit the loading and unloading of clothes to and from the basket 15 through a horizontal opening 16 in the top of the casing section 10. The horizontal opening 16 is provided with a downwardly extending peripheral flange 17 which is slightly curved at 18 where it joins the periphery of the opening 16 in order to provide a pleasing, stream-lined appearance and in order to be sure that there will be no snagging or catching of the clothes being inserted or withdrawn from the machine and also to provide a surface which is easy to clean and from which the coating material, such as porcelain, will not be likely to chip or mar.

The downwardly extending flange 17 is received in telescopic fashion within the upturned extremity 19 of a flange 20 which is secured to the periphery of an opening 21 at the top of the tub 14, which opening is slightly smaller than the opening 16 in the casing 9 and which is adapted to substantially register with the opening 16 when the machine is at rest. The flange 20 is curved inwardly at 22 to form a substantially horizontal shelf extending underneath the lower extremity of the flange 17. While, for convenience of presentation and explanation, the inwardly curved portion 22 of the flange 20 is described as "substantially horizontal," it generally will be found preferable to form this shelf portion with a slight downwardly and inwardly extending tilt so that any moisture, etc. formed or deposited on the flange 20 as when moist or wet clothes are inserted or withdrawn will be directed into the opening 21.

Inwardly of the shelf portion 22 the flange 20 is turned downwardly at 23 to provide a seat for a door 24 which is hingedly secured to the shelf portion 22 by hinges 25 and is latched thereto by handle operated latch 26. The door 24 is provided with a suitable rubber gasket 27 to insure a water-tight fit between the door 24 and the seat 23. As will be apparent from the drawing, the door 24 is smaller than the opening 16 in the casing 9 and may readily be pivoted to and fro within the enclosure provided by the flange 17. The basket 15 is provided with a closure member 28 which may be opened to provide access to the interior of the basket 15 and which is adapted to register with the opening 21 in the tub 14 and hence with the opening 16 in the casing 9 at a predetermined rotated position of the basket 15.

By reason of the above-described construction, a passageway is provided between the casing 9 and the tub unit 13 which is fully enclosed by the flange 17 or by the flanges 17 and 20. During the operation of the device, there is provided a sufficient overlapping of the flanges 17 and 20 so that the tub unit 13 may move from an upper fluid extracting position to a lower washing position without opening the passageway, i. e., vertically separating the flanges 17 and 20, and at the same time there is provided sufficient spacing between the flanges 17 and 20 so that there will be no engaging or binding between these flanges when the tub unit 13 undergoes the gyroscopic and vibrational movements previously referred to.

Even though there is no positive engagement between the opening in the casing and the opening in the tub structure, the only gap in the passageway is at the periphery of the upward extremity 19 of the flange 20 which is adequately protected by reason of its position well above the lower edge of the flange 17 to effectively prevent water or dirt from getting into the casing, and also to prevent any clothes being inserted or withdrawn through the passageway from passing into the interior of the casing. At the same time, the flange 20 provides an effective seat for a closure member for the tub unit and provides a drainage area emptying into the tub unit opening so that the loading and unloading of wet or damp clothes will have no deleterious effects on the machine. The passageway provided is of pleasing appearance and may readily be kept in sightly and sanitary condition.

It thus will be seen that, in accordance with the invention, there has been provided a simple and effective arrangement for permitting the loading and unloading of clothes to the tub unit of the machine which is effective regardless of the raised or lowered position of the tub unit and which will not interfere in any way with the normal operation of the machine. At the same time, the loading and unloading passageway is entirely effective for preventing moisture or dirt from passing into the casing sections 10 and 11 which might cause damage to the operating parts.

The device is simple and easy to manufacture and has no elements which can malfunction even after long periods of hard usage.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

It is also to be understood that the language used in the following claims is intended to cover all of the generic and specific features of the invention herein described and all statements of the scope of the invention which, as a matter of language, might be said to fall therebetween.

I claim as my invention:

1. In a laundry machine, a stationary outer casing having a top and sides, a horizontal tub structure having a longitudinal axis, said tub structure being resiliently mounted within the casing for limited movement relative to the casing in a plane radial to said axis including movement from an upper fluid extracting position to a lower washing position upon the admission of cleaning fluid to the tub, a basket rotatably mounted in said tub, an inwardly turned flange on the top of the casing forming a loading and unloading opening through the top of the casing, a flange on the tub having a laterally extending portion disposed underneath and spaced from the lower extremity of said casing flange, and a peripheral extension on said horizontal portion telescopically surrounding the casing flange and spaced therefrom whereby said relative movements of the tub structure are permitted, said tub being formed with an opening registering with said casing opening.

2. In a laundry machine, a stationary outer casing having a top and sides, a horizontal tub structure having a longitudinal axis, said tub structure being resiliently mounted within the

casing for limited movement relative to the casing in a plane radial to said axis including movement from an upper fluid extracting position to a lower washing position upon the admission of cleaning fluid to the tub, a basket rotatably mounted in said tub, an inwardly turned flange on the top of the casing forming a loading and unloading opening through the top of the casing, a flange on the tub having a laterally extending portion disposed underneath and spaced from the lower extremity of said casing flange, a peripheral extension on said horizontal portion telescopically surrounding the casing flange and spaced therefrom whereby said relative movements of the tub structure are permitted, said tub being formed with an opening registering with said casing opening, said horizontal portion of the tub flange forming a seat for a door, and a door hingedly secured to the tub flange to seat thereon and to pivot within the opening formed by said casing flange.

3. In a laundry machine, a stationary outer casing having a top and side walls, a tub structure resiliently mounted within said casing for substantial but limited movement relative to said casing, an inwardly turned flange integral with the top wall of said casing forming a loading and unloading opening through the top of said cas-

ing, a flange on the tub having a laterally extending portion disposed underneath and spaced from the lower extremity of said casing flange, a peripheral extension on said horizontal portion telescopically surrounding said casing flange and spaced therefrom whereby relative movements of said tub structure are permitted, said tub being formed with an opening registering with the casing opening, said horizontal portion of said tub flange forming a seat for a door, and a door hingedly secured to said tub flange to seat thereon and to pivot within the opening formed by said casing flange.
